UNITED STATES PATENT OFFICE.

EDWARD L. GAYLORD, OF BRIDGEPORT, CONNECTICUT.

TOOL FOR BEVELING AND FINISHING THE EDGES OF WOODEN PICTURE-MATS.

SPECIFICATION forming part of Letters Patent No. 313,196, dated March 3, 1885.

Application filed September 3, 1884. (No model.)

To all whom it may concern:

Be it known that I, EDWARD L. GAYLORD, a citizen of the United States, residing at Bridgeport, in the county of Fairfield and 5 State of Connecticut, have invented certain new and useful Improvements in Tools for Beveling and Finishing the Edges of Wooden Picture-Mats; and I do hereby declare the following to be a full, clear, and exact description 10 of the invention, such as will enable others skilled in the art to which it appertains to make and use the same.

My invention relates to certain novel and useful improvements in devices for beveling 15 and finishing the edges of picture-mats, and has for its object to provide a device of this description by means of which an ovolo or other desired surface may be given to the edge of the opening of a picture mat or frame, and 20 is so constructed that stock of greater or less thickness may be worked; and with these ends in view my invention consists in the details of construction and combination of elements hereinafter fully and in detail explained, and 25 then specifically designated by the claims.

In order that those skilled in the art to which my invention appertains may more fully understand its construction and operation, I will proceed to describe the same in 30 detail, referring by letter to the accompanying drawings, forming part of this specification, in which—

Figure 1 represents a side view of my improvement in operative position, with the material to be worked shown in section; Fig. 2, 35 a top view of Fig. 1; and Fig. 3, a central vertical longitudinal section through the handles, showing the blade in elevation, the method of securing the same, and the strip in position in the recess.

Similar letters denote like parts in the several figures of the drawings.

A B are handles, which I preferably form by casting from metal, handle A having the 40 downwardly-projecting gage I; and C D are plates adapted to be secured upon the tops of said handles by screws E or other suitable

means. Both the handles and plates aforesaid are recessed—the former upon their upper, the latter upon their lower, sides. These recesses correspond in position, and the blade F lies therein, and is clamped and held by the drawing together of the handles and plates by the screws.

In the bottom of the recess in handle A are 5 formed notches G, within which rests the downwardly-turned end of the flat metal strip H. The free end of this strip projects outward beyond the inner end of the handle, and lies against the lower side of the blade, thus preventing the latter from gouging the wood or cutting away the edge thereof next the gage. As the blade is held by clamping between the plates and handles, it will be adjustable longitudinally at any point for the accommodation 6 of stock of any thickness. It is triangular in cross-section, with the apex of the triangle at the top.

It is intended that blades of various cutting contours be used with the same handles, 70 as they are readily removable.

Having thus described my invention, what I claim as new, and desire to secure by Letters Patent, is—

1. In combination with the handle, recessed 75 as described, and having secured therein the blade, a metal strip lying in the recess and against the lower side of the blade, whereby the latter is prevented from cutting the edge of the wood next the gage, substantially as described.

2. The combination of handles A B, constructed and recessed as described, blade F, plates C D, adapted to clamp the blade to the handles, and strip H, lying in the recess of 85 the handle and against the bottom of the blade, all arranged as described, and for the purpose specified.

In testimony whereof I affix my signature in presence of two witnesses.

EDWARD L. GAYLORD.
